UNITED STATES PATENT OFFICE.

ROBERT P. McCURDY, OF PITTSBURGH, PENNSYLVANIA, AND FREDERICK W. HOCHSTETTER, OF DAYTON, OHIO, ASSIGNORS TO JOSEPH C. TREES, OF PITTSBURGH, PENNSYLVANIA.

HEADLIGHT.

Application filed May 23, 1924. Serial No. 715,408.

To all whom it may concern:

Be it known that we, ROBERT P. McCURDY, a resident of Pittsburgh, county of Allegheny, and State of Pennsylvania, and 5 FREDERICK W. HOCHSTETTER, a resident of Dayton, county of Montgomery, and State of Ohio, citizens of the United States of America, have invented certain new and useful Improvements in Headlights, of which 10 the following is a full and clear specification.

One object of this invention is to provide a headlight structure which will illuminate the roadway by indirect lighting, to thereby eliminate glare; and another object of the 15 invention is to provide a visor which shall not only be adjustable with respect to the front lens, but also be capable of use as a reflector to throw some of the rays of light upwardly and forwardly to thus enable the 20 visor to be used as a sort of spotlight for reading signs along the roadway, as more fully hereinafter set forth.

In the drawing—

Fig. 1 is a front view and 25 Fig. 2 is a vertical longitudinal sectional view showing one embodiment of our invention;

Fig. 3 is a detail view of the means for adjusting and locking the visor-reflector;

30 Figs. 4 and 5 are views of a modification; Figs. 6, 7 and 8 are views of another modification;

Fig. 9 is a perspective view, partly in section, showing a hollow prism.

35 Referring to Figs. 1, 2 and 3 of the drawing annexed, by reference-characters, 10 designates a pair of electric lamp bulbs supported within a lower reflector 11 at opposite sides of the same. This reflector faces upwardly and its open upper side is covered by a lens 12.

40 Mounted on the lower reflector is an upper reflector 13 of suitable shape to receive the direct as well as the reflected rays from the lower lamp chamber and reflect the same out through the usual front lens or glass 14. It will be understood that any suitable system of lenses may be employed. It will be observed that with our system of double reflectors, but a very small quantity of the direct rays will be projected out through the front lens and those rays that do escape directly through the front lens will be directed upwardly and thus be rendered ineffective

in having any binding action on the eyes 55 of approaching drivers. Practically all of the rays from the light source will be caught by the upper reflector and projected through the front lens in the form of a light flood, thereby entirely eliminating the objectionable glare which results from direct light. We have shown a plurality of light sources within the reflecting area, but it will be understood that one bulb alone may be used; the object in using a plurality of bulbs is 60 to increase illumination and compensate for the loss of light that occurs through indirect lighting.

Upon the front, upper side of the lamp housing, we hinge a visor 15 which is adapted to be swung down to a position against the lens 14 or to be swung upwardly to any desired position, means being provided for locking the visor in its adjusted position, said means consisting, for example, of a rod 70 16 extending to a point within easy reach of the driver and attached to a simple form of locking ratchet 17. The inner face 18 of the visor is silvered or treated in any other suitable manner to produce a reflecting-surface.

When the visor is swung down against the lens, it acts simply as a visor, but when swung away from the lens, it acts also as a reflector, receiving the rays from the upper reflector and throwing them downwardly upon the roadway or upwardly and forwardly, according to its adjusted position. When swung to the position shown in full lines, Fig. 2, it will be observed that the reflector 85 surface will throw the rays upwardly and forwardly in such manner as to illuminate a road-sign or other object located too high for illumination by the rays directly from the main reflector 13. In this way, the visor is adapted to be used in the manner of a spotlight. It will be understood that this spotlight visor may be employed with advantage on other types of headlight.

In the modification shown in Figs. 4 and 5, we use instead of the two lenses a prism 95 which is constructed to present a flat surface 20 to the light source and has its rear side 21 inclined upwardly and forwardly and silvered to provide a reflecting surface. It will be understood that we may use a hollow prism, as shown in Fig. 9, instead of

the solid prism illustrated. Whether hollow or solid, the vertical side walls 23 will be silvered or otherwise treated to produce a reflecting surface to thereby avoid losing any light through absorption by the side walls. This hollow prism may be built up of flat plates of glass fastened together at their corners by cement or otherwise.

In Fig. 2 and in the modification shown 10 in Figs. 6, 7 and 8, we provide the lens 12 with a translucent area 22 immediately above the lamp bulb; the object of this is to prevent the image of the incandescent filament from being reflected out through the 15 front lens, to thereby avoid any possibility of being blinded by the filament at what-

ever angle a person approaching the headlight may view the headlight.

What we claim is:

A headlight embodying a lower reflector 20 facing upwardly, light sources near the peripheral edge of the reflector, and an upper secondary reflector positioned above the light sources to receive the light rays from the lower reflector and project them forwardly, a lens disposed between the two reflectors, said lens having a translucent area 25 immediately above the rear light source.

In testimony whereof we hereunto affix our signatures this 16th day of April, 1924. 30

ROBERT P. McCURDY.

FREDERICK W. HOCHSTETTER.
